ATTORNEYS.

UNITED STATES PATENT OFFICE.

PHILMORE F. SPERY, OF CHICAGO, ILLINOIS.

RADIATOR FOR INTERNAL-COMBUSTION ENGINES.

1,349,011.

Specification of Letters Patent. Patented Aug. 10, 1920.

Application filed October 28, 1919. Serial No. 334,038.

To all whom it may concern:

Be it known that I, PHILMORE F. SPERY, a citizen of the United States, and resident of the city of Chicago, in the county of

5 Cook and State of Illinois, have invented certain new and useful Improvements in Radiators for Internal-Combustion Engines; and I do hereby declare that the following description of my invention, taken 10 in connection with the accompanying sheet of drawings, forms a full, clear, and exact specification, which will enable others skilled in the art to which the said invention appertains to make and use the same.

15 This invention has general reference to improvements in radiators for motor driven vehicles in which the motive power is derived from an internal combustion engine which is cooled by water surrounding the 20 cylinders, and which water is conducted to a device, termed "radiator," in which the water passes through air-cooled tubes to part with a portion of its heat, which water is then returned to the engine and thus circulates 25 between the engine and the radiator. This invention is especially directed to the construction of these water tubes; and it consists, essentially, of the novel and peculiar combination of parts and details of 30 construction, as hereinafter first fully set forth and described, and then pointed out in the claims.

The object of this invention is the production of a radiator possessing efficiency in 35 a high degree, combined with simplicity of construction. It is an improvement upon the device disclosed in the Letters Patent of the United States granted to me on the 23d day of September, 1919, No. 1,316,858.

40 In the drawings forming a part of this specification—

Figure 1 is a plan view of a fragment of a blank from which the fins for the water tubes are formed. Fig. 2 is a side elevation 45 of a water tube to which the fins are attached. Fig. 3 is a front elevation of an associated pair of water tubes with their radiating fins. Fig. 4 is a plan of a blank for radiator fins slightly modified; and Fig. 5 is a front elevation of a pair of water tubes supplied with the modified form of fins. Fig. 6 is a plan of a jig which is used in placing the fins onto the water tubes. Fig. 7 is a sectional view on line 7—7 of Fig. 6. Fig. 8 is an end elevation of this 55 jig.

Like parts are designated by the same characters and symbols of reference in all the various figures.

A, in the drawings designates the water tubes, and B, the fins associated therewith. These water tubes are oblong in transverse section and perfectly smooth on their exterior surface. They are placed into a radiator core in parallel relationship, and 60 spaced apart the proper distance. Each of these tubes is surrounded by a multiplicity of laterally extending fins; and these fins are constructed in the following manner:

A ribbon of sheet metal, preferably copper or brass, is perforated with a series of oblong holes 12, equally spaced, and of a size to admit the tube A by a close fit. This strip is then punched in a suitably constructed die to afford elongated ovates 13, 65 having parallel sides and approximately semi-circular ends, in which the oblong holes 12 are centrally located. These elongated ovates constitute the fins, and they are connected by strips or bars 14, of proper width, 70 medially of their sides, as illustrated in Fig. 1. This fin-strip is then bent at right angles along the dotted lines 15, 16, and then again bent at right angles along the dotted lines 17, 18. The portions 19, 20, of the bars 14 75 are then bent upon the side-portions 21, 22, of the elongated ovates, whereby all the ovates or fins will be brought into horizontal parallelism, as illustrated in Fig. 2, and connected to each other by the medial portions 23, of the bars 14. In this condition 80 the strip of fins is placed into a form or jig C, which jig has a longitudinal groove 24, of a width corresponding to the exterior flat dimension of the water tube and of 85 proper depth. This groove 24 is crossed by a series of channels 25, of sufficient size 90 to admit the elongated ovates, depressions 26, being alternately formed in one, and then in the opposite side walls of the groove 24 to admit the central portion 23 of the bars 14. An end plate D, is removably secured at one end of the jig C, preferably by 95 screws 27. When a strip of fins has been properly located in the jig C, a water tube 100 A is pushed through the opening 28, in the end plate D and passed through all of the oblong openings 12 in the fins, the tube being 105 guided by the longitudinal groove 24, and then the tube with its fins snugly held there- 110 to, is removed from the jig and the end plate D removed from the tube, and then the tube

is dipped into a bath of molten solder, whereby all the fins are connected to the tube, the members 23 being located alternately on one, and then at the other flat portions of the tube, thereby augmenting the adhesive connection of the fin with the tube, while at the same time the portions 19, 20, of the bars 14 underlying the portions 21, 22, of the elongated ovates serve as reinforcements for the same, and thereby produce a water tube of superior merits.

When seen from the front or the back of a radiator core, this construction has a square cellular appearance which is very much desired and in vogue at the present time.

In order to produce a core for a radiator, a proper number of water tubes are assembled, preferably in a clamping device similar to a printer's chase and locked there-in, and then the core is dipped with its face into a bath of molten solder, and then reversed to treat the back of the core in the same manner. This clamping process has a tendency to disarrange the square openings by the fins sliding upon one another, it being borne in mind that these fins are formed of very thin metal; and to overcome this tendency, a plain strip of metal 29, may be placed between adjacent ends of the fins, as illustrated in Figs. 3 and 5.

While I prefer the construction hereinbefore described, owing to its efficiency, a slight change, however, may be made therein; and in Fig. 4 I show a fin strip in which the elongated ovates are the same as heretofore described, but the distance between these ovates is shortened. This strip is bent at right angles along the dotted lines 30, 31, which brings the fins into parallel alinement so that the strip when placed into the jig as hereinbefore mentioned, is in condition to receive the water tube. This construction has the members 34 connecting the members 35, 36, of the elongated ovates in the folded condition alternately at one, and then at the other, outer margins of the members 13^a, which, while it affords the square cellular formation, is not quite as strong and rigid as the preferred embodiment of my invention, but it has the advantage of requiring less metal than the former construction; and where the cost of a core is an item of consideration, may be usefully employed.

I have hereinbefore stated that the fins of adjacent water tubes are separated by a plain flat bar; but it is evident that when the water tubes are spaced sufficiently apart that the fins cannot touch each other, this separating bar can be dispensed with without appreciably affecting the efficiency of the radiator.

A series of water tubes to make the core

for a radiator are always connected at their upper and lower ends to plates which form a part of the upper and lower water reservoirs; but this construction is so well known that I do not consider it necessary to illustrate this feature in the drawings.

Having thus fully described this invention, I claim as new, and desire to secure to myself by Letters Patent of the United States—

1. A radiator core, comprising, in combination, a multiplicity of vertical water tubes in parallel spaced apart relationship, each of said water tubes being an oblong tube having smooth flat sides and rounded edges, there being on said tube a series of laterally extending fins, said fins being elongated ovates having parallel sides and rounded ends, said fins being each perforated by oblong openings fitting the water tubes by a tight fit, said fins being connected at their sides by bars, said bars being bent and rebent to place the ovates into parallel alinement, said fins being connected to said tubes by being soldered thereto.

2. A radiator core, comprising, in combination, a multiplicity of vertical water tubes in parallel spaced apart relationship, each of said water tubes being an oblong tube having smooth flat sides and rounded edges, there being on said tube a series of laterally extending fins, said fins being elongated ovates having parallel sides and rounded ends, said fins being each perforated by oblong openings fitting the water tubes by a tight fit, said fins being connected medially of their sides by bars, said bars being bent and rebent to place the ovates into parallel alinement, the middle portions of said bars being in close contact alternately with one, and then with the other flat side of the water tube, the whole being connected by solder.

3. A radiator core, comprising, in combination, a multiplicity of vertical water tubes in parallel spaced relationship, each of said water tubes being oblong in cross section and having flat sides, there being on said water tubes laterally extending fins, said fins being elongated ovates having flat sides and rounded ends, said fins being connected medially of their sides, by bars, said bars being bent upon the sides of said fins from which they project, said fins having the medial portions of said bars contacting with said water tubes, adjacent water tubes having their fins separated by plain flat strips of metal as described.

In testimony that I claim the foregoing as my invention, I have hereunto set my hand.

PHILMORE F. SPERY.
